UNITED STATES PATENT OFFICE.

ERNEST H. RUEDIGER, OF BISMARCK, NORTH DAKOTA.

ELECTRIC THERMO-REGULATOR.

1,398,281.

Specification of Letters Patent. Patented Nov. 29, 1921.

Application filed April 28, 1920. Serial No. 377,313.

To all whom it may concern:

Be it known that I, ERNEST H. RUEDIGER, a citizen of the United States, residing at Bismarck, in the county of Burleigh and State of North Dakota, have invented certain new and useful Improvements in Electric Thermo-Regulators, of which the following is a specification.

This invention relates to a thermally controlled circuit closing device.

The object of the invention is to provide a thermo-regulator of the type in which a circuit is closed by the expansion or contraction of a liquid contained therein adapted to respond to slight variations in temperature and to be readily and accurately adjusted to close the circuit at different temperatures.

Another object is to provide a device of this character in which a float is operated by the liquid to permit the circuit closing means to be actuated at varying temperatures.

Another object of the invention is to produce a thermostatic circuit closer provided with means for displacing a fluid, preferably mercury, or to cause the fluid to occupy a minimum space within the casing, whereby the circuit closer may be caused to operate at various degrees of temperature.

Another object of the invention is to provide a circuit closer of this character wherein a float is actuated by the fluid to permit the circuit closed to be operated at various degrees of temperature.

With the foregoing and other objects in view, which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

The accompanying drawing represents a vertical section of a thermostatic closer constructed in accordance with this invention.

In the embodiment illustrated a cylindrical casing or tube 1 is shown, preferably constructed of an inner member 2 of iron or other material which will not be affected by mercury or which will not affect the mercury. This inner casing 2 is preferably sur-

rounded by an outer casing 3 which will pre-

vent the iron from rusting and which may be of an ornamental character.

The casings 2 and 3 are provided at their open ends with outwardly projecting annular flanges 4 and 5, which are designed to support a flange 7 of a plug 6 of fiber or other insulating material which is inserted in the open end of the shell and is secured thereto by fastening elements 8 passing through the flanges 4 and 5 and into flange 7.

This fiber plug 6 conforms in shape to the shell in which it is mounted and has a bore 9 extending centrally and longitudinally therethrough. The inner end of this plug 70 has a cone-shaped recess 10 merging at its apex or inner end into the bore 9 and which is designed for a purpose hereinafter to be described.

The plug 6 also has a longitudinal passage 75 11 extending therethrough parallel with the bore 9 and which is designed to receive an adjustable bar or rod 12. This rod 12 is provided at its outer end with a head 13 to form a finger grip to facilitate the adjustment of the rod which is held in adjusted position by a set screw 14, passing through the flange 7 of the plug and binding on the rod 12.

The shell 1 is designed to contain mercury 85 or other suitable liquid and has a float 16 mounted to move vertically in the bore 9 so that when the fluid level in said bore raises or lowers the float will be shifted either upwardly or downwardly and the cone-shaped 90 recess 10 at the lower end of the plug will operate to cause a relatively small movement of the liquid within the lower portion of the shell to produce a considerably greater movement of the liquid within the bore 9, 95 the walls of the said recess 10 operating to direct the fluid up into the bore.

A stem or shank 17 extends upwardly from the float 16 and is pivoted to a lever 18 intermediate its ends. This lever 18 is fulcrumed at one end to a standard 19, which rises from the outer face of plug 6.

A binding post 20 in the form of an L-shaped bracket secured to the flange 7 of the plug 6 is arranged in the path of movement 105 of the free end of lever 18 with which one wire of an electric circuit is connected, the other wire being connected with the binding post 20.

From the above description it will be ob-

vious that when the float 16 moves downwardly, which will be caused by the contraction of the fluid 15, the lever 18 will contact with the binding post 20, thereby closing the electric circuit which may be connected to sound an alarm or to control any other device. When the fluid level within the bore 9 rises the float 16 will rise and thus swing the lever 18, which constitutes one member of a switch, out of engagement with the binding post 20 and thereby break the circuit.

It will be understood that the change in level of the fluid 15 will be caused by changes in temperature surrounding it, that is when the temperature rises, the fluid will expand and move upward in the bore 9 to break the circuit and when it lowers the fluid will contract and the float will be lowered correspondingly to close the circuit.

20 The adjustable rod 12 is designed to displace a greater or less amount of the fluid 15 so as to cause a corresponding adjustment of the normal level of said fluid in the bore 9.

It will thus be seen that when the rod 12 is moved downwardly into the shell, a certain amount of fluid 15 will be displaced thereby which will rise into the bore 9 and when this rod is raised the fluid in the bore will move downwardly to take the position occupied formerly by the rod thereby lowering the level of the fluid in bore 9. This change in the level of the fluid in bore 9 is designed for controlling the closing of the switch to adapt it to be closed at any desired temperature.

From the foregoing description, taken in connection with the accompanying drawings, the advantages of the construction and the method of operation will be readily apparent to those skilled in the art to which the

invention appertains and while I have described the principle of operation of the invention together with the device which I now consider to be the best embodiment thereof, I desire to have it understood that the device shown is merely illustrative and that such changes may be made as are within the scope of the claimed invention.

What is claimed is:—

1. In a device of the class described, the combination of a shell having an expansible liquid therein, an insulating plug carried by said shell and having a longitudinal bore extending therethrough, a standard rising from said plug, a switch lever fulcrumed on said standard, a float movable in said bore on the surface of said liquid, a shank connecting said float with said lever, and a binding post carried by said plug in the path of movement of said lever, whereby when the float is lowered the lever will engage the post to close a circuit and the rising of the float will disengage said lever and break the circuit.

2. In a device of the class described, the combination of a shell having an expansible fluid therein, a plug of insulating material mounted in one end of said shell and having a bore extending longitudinally therethrough with a cone-shaped recess in its inner end merging into said bore, a switch lever carried by said float, a binding post mounted on said insulated plug, in the path of movement of said lever, circuit wires connected with said lever and post, and an adjustable fluid displacing element mounted in said plug.

ERNEST H. RUEDIGER.
